UNITED STATES PATENT OFFICE.

RICHARD F. OUTCAULT, JR., OF CHICAGO, ILLINOIS.

DESIGN FOR A LEAF FOR A BANK DEPOSIT BOOK

Application filed January 15, 1927. Serial No. 20,391. Term of patent 14 years.

To all whom it may concern:

Be it known that I, RICHARD F. OUTCAULT, Jr., a citizen of the United States, residing at Chicago, in the county of Cook and State of Illinois, have invented a certain new, original, and ornamental Design for a Leaf for a Bank Deposit Book, of which the following is a specification, reference being had to the accompanying drawing, forming part thereof.

The figure is a plan view on an enlarged scale of a leaf for a bank deposit book showing my new design.

I claim:

The ornamental design for a leaf for a bank deposit book, as shown.

RICHARD F. OUTCAULT, JR.
